CRADLE FOR TOP APRONS AS USED IN HIGH-DRAFT SYSTEMS

Howard E. Kuehn and Ross B. Newton, Whitinsville, Mass., assignors to Whitin Machine Works, Whitinsville, Mass., a corporation of Massachusetts

Application April 8, 1953, Serial No. 347,508

2 Claims. (Cl. 19—131)

1
This invention relates to high-draft systems by which yarn or roving is produced. In such systems, the drafting operation may involve the use of a relatively long bottom apron and a slip-roll associated therewith. A second construction involves the use of a relatively long bottom apron and a relatively short top apron which passes around the middle top roll which replaces the slip roll previously described.

It is the general object of our invention to provide an improved cradle or apron support to be used in the second construction. This cradle is designed so that it may be easily applied or conveniently removed, when and as desired.

More specifically, we provide a cradle having slight inherent resilience and so constructed that it will firmly grip a fixed guide-bar associated with the bottom apron.

Our invention further relates to arrangements and combinations of parts which will be hereinafter described and more particularly pointed out in the appended claims.

A preferred form of the invention is shown in the drawings, in which:

Fig. 1 is a sectional end elevation of parts of a drawing frame embodying our invention;

Fig. 2 is a perspective view of our improved cradle in attached position;

Fig. 3 is a detail view of a guide-bar;

Fig. 4 is a diagrammatic view indicating how our improved cradle is attached to the permanent or fixed guide-bar;

Fig. 5 is a front elevation showing a detail modification; and

Fig. 6 is a sectional side elevation, taken along the line 6—6 in Fig. 5.

Referring to Fig. 2, our improved cradle comprises side plates 10 and 11, spaced apart and held in fixed relation by a cross bar 12 which also acts as a guide-bar for the top apron. The ends 14 of the bar 12 are reduced in size to provide shoulders and are inserted and secured in slots 15 in the side plates 10 and 11.

The drafting assembly with which our improved cradle is to be used is shown in Fig. 1, in which a relatively long bottom apron 20 is driven by the middle bottom roll 21 and passes around a fixed guide-bar 22 and a yieldingly-mounted weighted tension roll 24.

The usual front rolls 30 and 31 and the usual back rolls 32 and 33 are also provided, and a relatively short top apron 40 passes around a middle top roll 41 and around the guide-bar 12 previously described.

The side plates 10 and 11 are made of some material, such as plastic, which has a slight amount of inherent resilience, and the cradles are attached in place by hooking the lugs 50 thereof over the fixed guide-bar 22 and then snapping the ends of the depending arms 52 around the 60

lower edge of the guide-bar. The inherent resilience of the side plates will then hold the cradle firmly in operative position, but will permit easy removal when desired.

5 The upwardly extending arms 53 of the side plates are convenient in applying pressure when attaching the cradles to the bar 22, and they also provide additional side surface for guiding the edges of the top apron 40. A slightly modified construction is shown in Figs. 5 and 6 in which side plates 60 and 61 are held in fixed relation by a cross bar 62 and are provided with depending arms 63 and 64, all as shown in the previous construction. The lower inside face of each side plate is relieved as indicated at 66 and 67 to provide clearance and thus avoid chafing the edges of the top apron. The arms 63 and 64 may also be narrower in their upper portions as shown at 70 to increase their resilience.

10 It will be particularly noted that no tools are required for attaching or removing these cradles, and that the cradles and top aprons may be placed in operative position without stopping the rotation of the bottom rolls 21, 30 and 32. The drawing frames may thus be easily changed from single-apron to double-apron operation and vice-versa as desired.

Having thus described our invention and the advantages thereof, we do not wish to be limited to the details herein disclosed, otherwise than as set forth in the claims, but what we claim is:

15 1. A cradle for the top apron of a double apron high-draft system having a fixed guide-bar for the bottom apron, said cradle comprising spaced side plates and a connecting cross bar which acts as a guide-bar for the top apron, said side plates being inherently resilient and having spaced gripping portions which are yieldable for firmly seating said cradle on said fixed guide-bar.

20 2. A cradle for the top apron of a double apron high-draft system having a fixed guide-bar for the bottom apron, said cradle comprising spaced side plates and a connecting guide-bar, said side plates each having a shoulder to engage one edge of said fixed guide-bar and having an integral hooked arm to engage the other edge of said fixed guide-bar, and said arms being inherently resilient and slightly yieldable and being effective to firmly seat said cradle on said fixed guide-bar.
